UNITED STATES PATENT OFFICE.

CHARLES T. WESTLAKE, OF ST. LOUIS, MISSOURI.

INTERNAL-COMBUSTION ENGINE.

1,313,033.

Specification of Letters Patent. Patented Aug. 12, 1919.

Application filed July 30, 1915. Serial No. 42,715.

To all whom it may concern:

Be it known that I, CHARLES T. WESTLAKE, a citizen of the United States, residing at St. Louis, Missouri, have invented a certain new and useful Improvement in Internal-Combustion Engines, of which the following is a full, clear, and exact description, such as will enable others skilled in the art to which it appertains to make and use the same, reference being had to the accompanying drawings, forming part of this specification.

My invention relates generally to internal combustion engines and more particularly to the means for controlling the admission of the combustible vapor to the cylinder of the engine and the subsequent exhaust of the products of combustion.

The principal objects of my invention are, to generally improve upon and simplify the existing types of internal combustion engines and eliminate the puppet valves usually associated therewith; to arrange between the cylinder and the piston a sleeve or shell, the closed upper end of which serves as the fixed head for the chamber within the cylinder, said sleeve or shell being provided with suitably located openings which perform the functions of inlet and exhaust ports; to provide simple means for rotating the sleeve in proper time relation to the movement of the piston; to provide mechanically operated means for disseminating the heat generated during the operation of the engine, and further to provide means for distributing lubricating oil over the entire contacting surfaces between the sleeve and the cylinder.

With the foregoing and other objects in view, my invention resides in the combination and arrangements of parts and in the details of construction hereinafter more fully described and claimed, it being understood that various changes in the precise embodiment of the invention herein disclosed can be made without departing from the spirit of the invention.

In the drawings,

Figure 1 is a side elevational view of a four cylinder internal combustion engine constructed in accordance with my invention and with the crank case in vertical section.

Fig. 2 is an enlarged vertical section taken approximately on the line 2—2 of Fig. 1.

Fig. 3 is a horizontal section taken approximately on the line 3—3 of Fig. 2.

Fig. 4 is a detail section of a portion of the engine cylinder and showing a modified form of joint between the upper end of the sleeve and cylinder wall.

Fig. 5 is a vertical section taken through the center of a modified form of my improved engine.

Fig. 6 is a vertical section taken approximately on the line 6—6 of Fig. 5, and showing the rotary sleeve in elevation.

Figs. 7 to 11 inclusive, are diagrammatic views illustrating the position of the rotary sleeve at various periods during a complete cycle of operation.

Figs. 12 to 16 inclusive, are diagrammatic views which are complementary to Figs. 7 to 11 inclusive, and showing the relative positions of the crank, piston rod, and piston at various periods during a complete cycle of operation.

Referring by numerals to the accompanying drawings, 10 designates the engine cylinder, either water-jacketed as illustrated in Figs. 2 and 3, or provided with heat radiating webs or fins, as illustrated in Figs. 5 and 6.

It will be noted that the chamber within the cylinder is open at both ends and when said cylinder is properly assembled with other parts of the engine, the open inner end of the cylinder chamber communicates with the chamber within the crank case and the outer end of said cylinder chamber communicates with a chamber which receives fluid utilized in the cooling system of the engine.

Where a number of cylinders are combined, they are preferably cast *en bloc*, as illustrated in Fig. 1.

Secured in the usual manner to the lower portion of the cylinder is a crank case 11 in which operates the usual crank shaft 12. Connected in the usual manner to each crank of this shaft is the lower end of the usual connecting or piston rod 13, the upper end thereof being connected to a piston 14, which latter is slightly smaller in diameter than the internal diameter of the chamber within the cylinder 10, said piston being preferably provided with a series of packing rings 15.

A cylindrical sleeve 16 is mounted for rotary movement between the inner face of the chamber within cylinder 10 and the pis-

ton 14, the upper end of said sleeve being permanently closed by an integral or rigidly fixed head 17 and the lower end being extended a short distance below the lower 5 end of the cylinder and being provided with an annular row of gear teeth 18.

The lower inner edge of sleeve 16 is beveled as designated by 19 in order to perform the functions of a wedge to force the packing 10 rings into the grooves in the piston 14 when said piston is inserted or positioned within said sleeve. The upper end of the sleeve 16 is preferably provided with an outwardly projecting flange 20 which bears in 15 a corresponding groove formed in the upper end of cylinder 10 and formed integral with or fixed to the outer portion of head 17 is a spirally disposed flange or rib 21.

It will be noted that in my improved construction the head 17 which is a part of sleeve 16 performs the functions of a head for the engine cylinder 10.

Removably fixed to the upper end of cylinder 10 is a plate 22, the space 23 beneath 25 which communicates with the water space in the jacket around cylinder 10. It will be noted that the spiral flange 21 extends into the space 23 within head 22, and thus as sleeve 16 is rotated during the operation of 30 the engine, said flange will act as a centrifugal pump to maintain a circulation of water or other cooling medium through the cooling system utilized in connection with the engine.

35 Sleeve 16 is rotated directly from crank shaft 12, preferably by means of meshing beveled pinions 24 and straight pinions 25, one of which latter engages the teeth 18 of said sleeve, it being understood that these 40 pinions are of the proper relative sizes to drive the sleeve in proper time relation to the movement of the piston 14.

Formed through the upper portion of sleeve 16 are four openings 26, each of which 45 serves as an inlet port or an exhaust port, depending, of course, upon its position, and formed through the wall of cylinder 10 is an inlet port 27 and an exhaust port 28, the same being slightly offset diametrically of 50 the cylinder.

Formed in the cylinder 10 at a suitable point near port 27 is a firing chamber 29 in which is located the inner end of a spark plug 30, and formed in the inner face of cylinder 10 and leading from this firing chamber toward port 27 is a horizontally disposed groove or passage way 29^a. This passage way permits the burnt gases to exhaust from the firing chamber during the 60 exhaust stroke of the engine as hereinafter more fully described. A vapor supply pipe 31 leads to inlet port 27 and leading from port 28 is an exhaust pipe 32.

In the modification illustrated in Fig. 4, 65 the upper end of sleeve 16 is provided with

an outwardly projecting flange 33 which is substantially L-shape in cross section and which operates in a corresponding groove formed in cylinder 10. This construction is intended to provide a tight joint and minimizes leakage between the cylinder and 70 rotary sleeve.

In the modified construction illustrated in Figs. 5 and 6, the cylinder 10^a is provided with a series of heat radiating fins or webs 75 34 and the spiral flange 21^a on top of the sleeve 16^a is made of considerable depth in order to perform the functions of a centrifugal fan, which, when said sleeve is rotated, establishes a circulation of air over the top 80 or head 17^a of the sleeve to produce a cooling effect thereupon and upon the adjacent parts of cylinder 10^a.

In order to provide a bearing for the upper end of sleeve 16^a, a ring 35 is detachably secured in any suitable manner to the upper end of cylinder 10^a and formed in said ring and in the upper inner edge of cylinder 10^a are coinciding grooves 36 which receive an outwardly and upwardly projecting flange 90 37, the same being formed integral with the upper end of the sleeve.

In order to prevent leakage through this joint, the flange 37 is provided with a suitable packing ring 38. In order to lubricate 95 the contacting surfaces between the cylinder and the sleeve, a spirally disposed groove 39 is formed in the surface of said sleeve, said groove being arranged so as to carry a liquid lubricant upwardly during the rotation of 100 said sleeve, and thus the contacting surfaces are lubricated, and in addition, the lubricant contained in this groove serves as a packing to prevent the leakage of gas between the cylinder and sleeve. (See Fig. 1.) 105 This oil groove extends upwardly on the sleeve to a point near the lower ends of ports 26 and the upper portion of said groove communicates with vertically disposed grooves 39^a formed in the outer face of the 110 sleeve to the sides of said ports and the upper ends of said vertical grooves communicate with an annular groove 39^b, which latter is formed immediately beneath the flange at the upper end of sleeve 16^a. It will be 115 understood that this same arrangement of oil grooves can be formed in the outer face of sleeve 16.

During the operation of an engine of my improved construction, the piston reciprocates in the usual manner within the sleeve 16 and said sleeve is continuously rotated by means of the driving connections 24 and 25 from the crank shaft. At the beginning of the intake stroke, the sleeve 16, piston 14, 120 and rod 13 occupy the positions illustrated in Figs. 7 and 12, with one of the ports 26 just beginning to open or move into coincidence with inlet port 27.

During the downward movement of pis- 125

ton 14, this port 26 is in communication with port 27 and consequently a charge of combustible vapor is drawn into the chamber within sleeve 16. This intake stroke 5 is represented by the dotted lines *a*, Fig. 7.

At the time the piston begins its succeeding upward stroke to compress the combustible charge in the upper portion of the chamber within sleeve 16, port 26 passes 10 inlet port 27, thereby cutting off the further inlet of gas to the chamber and as the piston moves to the upper end of said chamber, the charge is compressed therein. This compression stroke is graphically illustrated 15 by means of the dotted lines *b*, Fig. 8.

When the piston 14 has reached its upper limit of movement to effect highest compression, the port 26 immediately to the rear of the port which was just in coincidence 20 with the inlet port 27 moves into coincidence with spark chamber 29 as illustrated in Fig. 9, and the timing apparatus associated with the engine is now actuated to produce a spark at the point of plug 30, thus 25 igniting the compressed charge and driving the piston 14 downward. This explosion stroke is graphically illustrated by the dotted lines *c*, Fig. 9.

On the succeeding upward or exhaust 30 movement of the piston 14, a port 26 is brought into coincidence with exhaust port 28, thus permitting the escape of burnt gases and after the particular port 26 passes firing chamber 29 and during the full period 35 of the exhaust stroke of the piston, said port is in communication with the groove 29* leading from the firing chamber, thus permitting all of the burnt gases which might otherwise remain in said firing chamber to 40 escape therefrom so that on the succeeding intake suction stroke of the engine, the entire chamber within the sleeve 16 and the firing chamber are practically free of burnt gases. This exhaust is graphically illustrated 45 by the dotted lines *d*, Fig. 10.

Immediately after communication is cut off between the exhaust ports and before one of the inlet ports 26 establishes communication with inlet port 27, the piston 14 50 moves a short distance downward, thereby producing a partial vacuum in the upper portion of the chamber within sleeve 16, such movement being graphically illustrated by the dotted lines *e*, Fig. 11, and this partial vacuum is effective in accelerating the drawing of the succeeding combustible charge into the engine cylinder on the succeeding intake stroke.

An engine of my improved construction 60 has comparatively few operating parts and by utilizing a rotating sleeve between the piston and cylinder and providing ports in said sleeve which are adapted to register with ports in the cylinder, all puppet valves 65 and the like such as are ordinarily associ-

ated with internal combustion engines, are dispensed with.

I claim:

1. In an internal combustion engine, an outer cylinder, an inner cylinder closed at 70 its outer end, said last mentioned cylinder being adapted to rotate within the first mentioned cylinder, both cylinders being provided with ports which are adapted to coincide as the inner cylinder is rotated, a 75 piston mounted for operation within the rotating cylinder, and means on said rotating cylinder for effecting a circulation of cooling medium around the outer cylinder and over the closed end of the inner cylinder. 80

2. In an internal combustion engine, an outer cylinder, an inner cylinder closed at its outer end, said last mentioned cylinder being adapted to rotate within the first mentioned cylinder, both cylinders being provided with ports which are adapted to coincide as the inner cylinder is rotated, a 85 piston mounted for operation within the rotating cylinder, means on said rotating cylinder for effecting a circulation of cooling medium around the outer cylinder and over the closed end of the inner cylinder, and means operatively connected to the piston for imparting rotary movement to the inner cylinder. 95

3. In an internal combustion engine, an outer cylinder provided with a chamber adapted to receive a cooling medium, a cylinder arranged for rotary movement within the outer cylinder, said inner cylinder being 100 closed at its outer end, both cylinders being provided with ports which are adapted to coincide as the inner cylinder is rotated, a piston mounted for movement within the inner cylinder, and means on said inner cylinder for effecting a circulation of cooling 105 medium through the chamber in the outer cylinder.

4. In an internal combustion engine, a cylinder provided with a chamber adapted to 110 receive a cooling medium and having inlet and exhaust ports, a sleeve mounted for rotary movement within said cylinder and closed at its outer end, said sleeve being provided with ports which are adapted to coincide with the inlet and exhaust ports in the outer cylinder, a piston arranged for operation within the sleeve, and means on the closed end of said sleeve for effecting a circulation of cooling fluid through the chamber 115 in the outer cylinder. 120

5. In an internal combustion engine, the combination with a relatively fixed cylinder provided in its wall with inlet and exhaust ports, of a cylindrical member mounted for 125 rotary movement within said fixed cylinder, the outer end of which rotary cylinder is closed to form a head for the chamber within said rotary cylinder, means on said head for disseminating heat, said last mentioned 130

- cylinder being provided with a port for controlling the inlet and exhaust ports in the outer cylinder, a piston operating within the rotary cylinder, and means for imparting movement to the rotary cylinder in proper time relation to the movements of said piston.
6. In an internal combustion engine, an outer cylinder, an inner cylinder mounted for rotary movement within said outer cylinder, said inner cylinder being closed at its outer end, and means on said closed end for disseminating heat as said inner cylinder is operated.
15. 7. In an internal combustion engine, a relatively fixed member provided with a port, a cylindrical member mounted for rotation within said member and provided with ports which are adapted to coincide with the port in said fixed member, a piston mounted for operation within the cylindrical member, said cylindrical member being closed at its outer end to form a head for the chamber in which the piston operates, and means on the closed end of said cylindrical member for disseminating heat.
8. In an internal combustion engine, the combination with an outer cylinder provided with inlet and exhaust ports, of a movable inner cylinder provided with a plurality of ports which are adapted to coincide with the ports of the outer cylinder, said inner cylinder being closed at its outer end, and means on said closed outer end for disseminating heat.
9. In an internal combustion engine, a cylinder provided with a chamber adapted to receive a cooling medium, a cylinder arranged for movement within said first mentioned cylinder, a portion of which inner cylinder projects into said chamber, and means on said inner cylinder for effecting a circulation of the cooling medium within said chamber as the inner cylinder is operated.
10. In an internal combustion engine, a relatively fixed cylinder, a piston, a movable sleeve between the piston and the cylinder, the outer end of which sleeve is closed, and a rib formed on said closed end for disseminating heat as said sleeve is operated.
11. In an internal combustion engine, a cylinder, a piston, a sleeve arranged for rotation between said cylinder and piston, one end of said sleeve being closed to form a head for the combustion chamber of the engine, and means on said closed end for disseminating a portion of the heat developed within the combustion chamber while the engine is in operation.
12. In an internal combustion engine, the combination with a cylinder and a piston therein, of a sleeve mounted for rotary movement between the cylinder and piston, one end of which sleeve is closed and pro-
- vided with means for disseminating heat while in operation, and there being a lubricant receiving groove formed in the external surface of said sleeve.
13. In an internal combustion engine, the combination with a cylinder and a piston therein, of a sleeve mounted for rotary movement between the cylinder and piston, one end of which sleeve is closed and provided with means for disseminating heat while in operation, there being a lubricant receiving groove formed in the external surface of said sleeve, said sleeve being provided with a plurality of ports which are adapted to coincide with ports formed in the cylinder, and means for rotating said sleeve.
14. In an internal combustion engine, a cylinder provided with a port, a piston, a sleeve arranged for rotation between the piston and cylinder, which sleeve is provided with a plurality of ports which are adapted to coincide with the port of the outer cylinder, there being a spirally disposed lubricant receiving groove formed in the outer face of said sleeve, and there being branch grooves leading from said spiral groove to points adjacent to the ports in said sleeve.
15. In an internal combustion engine, an outer cylinder provided with inlet and exhaust ports, a piston, a sleeve between said piston and cylinder, said sleeve being provided with ports which are adapted to coincide with the ports in the cylinder, said cylinder being provided with a firing chamber with which the ports in the sleeve are adapted to coincide and there being a groove formed in the inner face of the cylinder, which groove communicates with the firing chamber and projects in the direction in which the sleeve operates.
16. In an internal combustion engine, an outer cylinder provided with inlet and exhaust ports, a piston, a sleeve between said piston and cylinder, said sleeve being provided with ports which are adapted to coincide with the ports in the cylinder, and said cylinder being provided with a firing chamber with which the ports in the sleeve are adapted to coincide, which firing chamber is provided with a lateral extension.
17. In an internal combustion engine, an outer cylinder provided with inlet and exhaust ports, a piston, a sleeve between said piston and cylinder, said sleeve being provided with ports which are adapted to coincide with the ports in the cylinder, said cylinder being provided with a firing chamber with which the ports in the sleeve are adapted to coincide, and means for permitting the escape of burnt gases from the firing chamber after the ports in the sleeve have passed said firing chamber.
18. In an internal combustion engine, a cylinder provided with a firing chamber, means for producing a spark in said chamber.

ber, a piston, a sleeve mounted for rotary movement between the piston and cylinder, said sleeve being provided with ports which are adapted to coincide with the firing chamber, and means for permitting the passage of burnt gases from the firing chamber to the ports in the sleeve after said ports have passed said firing chamber.

19. In an internal combustion engine the combination of a cylinder open at both ends, of a relatively rotatable sleeve within said cylinder, a piston within said sleeve, the outer end of said sleeve being closed to form a head for the piston chamber, a plate on the outer end of the cylinder, which plate and closed end of the sleeve constitute the inner and outer walls of a cooling medium chamber and a flange on the closed outer end of the sleeve, which flange is effective in establishing a circulation of the cooling medium in said chamber when the sleeve is rotated.

20. In an internal combustion engine the combination of a cylinder open at both ends, of a relatively rotatable sleeve within said cylinder, a piston within said sleeve, the outer end of said sleeve being closed to form a head for the piston chamber, a plate on the outer end of the cylinder, which plate and closed end of the sleeve constitute the inner and outer walls of a cooling medium chamber, and a flange on the closed outer end of the sleeve, which flange is effective in establishing a circulation of the cooling medium in said chamber when the sleeve is rotated, the wall of said cylinder being provided with inlet and outlet ports, and said sleeve being provided with ports which are adapted to coincide with the ports in the cylinder.

40 21. In an internal combustion engine, the combination with a cylinder open at both

ends, of a sleeve mounted for rotation within said cylinder, a piston arranged for operation within said sleeve, the outer end of which sleeve is closed to form a head for the piston chamber, a plate on the outer end of the cylinder, which plate and closed end of the sleeve constitute the inner and outer walls of a cooling medium chamber, the walls of said cylinder and sleeve being provided with ports which are adapted to coincide, and means for imparting rotary movement to said sleeve in proper time relation to the reciprocating movement of the piston.

22. In an internal combustion engine, the combination with a cylinder open at both ends, of a sleeve mounted for rotation within said cylinder, a piston arranged for operation within said sleeve, the outer end of which sleeve is closed to form a head for the piston chamber, a plate on the outer end of the cylinder, which plate and closed end of the sleeve constitute the inner and outer walls of a cooling medium chamber, the walls of said cylinder and sleeve being provided with ports which are adapted to coincide, means for imparting rotary movement to said sleeve in proper time relation to the reciprocating movement of the piston, and there being a firing chamber formed in the inner face of the cylinder with which the ports in the sleeve are adapted to communicate.

In testimony whereof I hereunto affix my signature in the presence of two witnesses, this 17th day of July, 1915.

CHARLES T. WESTLAKE.
